KNITTED HAT AND PROCESS FOR MAKING THE SAME

Application filed May 28, 1931. Serial No. 540,536.

My invention relates to improvements in knitted hats and processes of making the same.

The primary object of my invention is to provide means for manufacturing a knitted hat in which the brim, crown and band may be formed integrally, regard being had for expedition in the manufacture of knitted hats, reduction in the cost of manufacture, improvement in the appearance of hats formed of knitted material, and improved retention of contour during prolonged use.

Further objects are to provide means for manufacturing hats from the same tube of material which will differ in appearance, which may be either single or double, which may have either an external roll or an external band at the base of the crown, which may have either an open or a closed crown and when made with an open crown will require no selvage edge or sewed border along the margin of the opening.

Further objects are to provide means for manufacturing from the same piece of knitted tubing hats with flexible brims and wave-like margins, hats with stiffened brims affording substantial resistance to flexion, and hats with distended brims resiliently reinforced.

30 In the drawings:

Figure 1 is a diagrammatic illustration of a knitted tube conforming to the usual product of what is known as a tubular knitting machine.

35 Figure 2 is an enlarged fragmentary view showing how a section of the tube may be folded and preliminarily shaped for the manufacture of a hat in one of the styles made possible by the process.

40 Figure 3 is a sectional view showing a fragment of the hat with the crown, band, brim and exposed roll substantially in their final relative positions and as the parts appear during a brim stretching operation.

45 Figure 4 is a view of the hat as it appears in use, a portion of the brim being broken away to show the re-enforcing and stiffening material.

Figure 5 is a sectional view of a fragment 50 of a similar hat in which the parts have been

inverted during the process of manufacture whereby to produce a hat with a cylindrical inner or head band and an outer flat band.

Figure 6 is a sectional view showing a fragment of a hat similar to the one shown in Fig. 4 except that it is formed with a double crown having an opening at the top closed by an inserted piece of knitted fabric separately formed.

Figure 7 is a view similar to Fig. 6 but with the crown portion gathered to eliminate the opening and avoid the necessity of inserting a separately formed piece.

Like parts are identified by the same reference characters throughout the several views.

In the manufacture of my improved hats I first form a knitted tube such as may be conveniently produced upon a tubular knitting machine. This tube may be knitted 70 with any form of stitch known to the art of knitting on tubular knitting machines, the type of stitch being immaterial to my invention, although in the manufacture of ordinary knitted hats by the process herein described, 75 it will be found convenient to knit the tube in a series of alternate sections A formed with a tuck stitch and a series of intermediate sections B formed with a plain stitch, the sections B of the tube forming connecting 80 neck portions of somewhat reduced diameter as compared with the sections A.

In forming a hat of the type shown in Figure 4 I cut the knitted tube transversely as indicated by the dotted lines a—a and b—b 85 in Fig. 1 and turn the blank thus produced, providing two members or sections A—A connected by one of the sections B and at the ends there may be half sections B, one of which will be permitted to roll up and 90 form a cylindrical band 10 as shown in Fig. 2. The other end may be gored and gathered to form the crown 11, the cut edges of the gofe being stitched together along curved lines leading to the top of the 95 crown as indicated at 13.

Thereupon the connecting section B will be folded at approximately its median annular line to form the double walled band 14. The upper member A and its associated upper half 100

section B may then be shaped to form the crown, whereupon the band 14 may be connected with the base of the crown by a line of stitching 15.

5 The lower portion A of the blank will then have its lower half folded or turned upwardly upon its upper half to bring its cylindrical roll 10 into proximity with the line of stitching 15 on the opposite side from that occupied by the band 14 and this folded portion A will be swung outwardly and secured in a horizontal position of radial extension by an inserted wire hoop 17, thereby forming a double walled brim having lower and upper walls 18 and 19 respectively. The cylindrical roll 10 will thereupon constitute an integrally knitted cord like band extending about the base of the hat crown, but it will be left unconnected therewith until the brim members 18 and 19 have been damped, stretched, and ironed, or if desired impregnated with suitable stiffening material. Also, if desired, a strip or annular sheet 20 of reinforcing material, preferably rubberized 25 fabric, may be inserted between the walls 18 and 19 and the brim may then be ironed and the knitted material more or less embedded in or impregnated with the rubber and caused to adhere to the re-enforcing sheet 20 where- 30 by the layers may be adhesively connected.

If desired the resilient ring 17 may be removed before inserting the re-enforcing material 20 and in that event the brim will normally assume the form in which it is illustrated in Figure 4, the brim having a wave like margin, whereas if the resilient ring 17 is left in place the band will be held under tension substantially in a horizontal plane extending outwardly from the lower margin 40 of the crown.

After the re-enforcing material has been inserted the cylindrical roll 10 may be stitched to the base of the crown by a line of stitching 22.

45 It is obvious that by reversing the hat shown in Figure 4, i. e. by turning it inside out, a hat may be produced of the type illustrated in Fig. 5 in which the roll 10 will be on the inner side and the band 14 will encircle the base of the crown on the outer side. By inverting the blank substantially at the stage of manufacture illustrated in Fig. 2, the cut edges along the gore lines may be turned inwardly and stitched without additional finishing, whereas if either the hat shown in Fig. 4 or a hat made as indicated in Fig. 5 is to be worn alternatively with the cylindrical band 10 and the flat band 14 exposed, it will of course be desirable to bind 55 or otherwise finish the margins of the gores in order that they will present a finished appearance on both sides as indicated in Figures 2 and 3.

It will sometimes be desirable to form a 60 hat with a double walled crown as well as a

double walled brim. In that event a blank may be cut from the tube of a length equal to that represented by three of the sections or members A with two intermediate sections B and end half sections B, whereupon the two upper sections A may be folded one upon the other along the central line of their intermediate or connecting section B to, form a double walled crown portion 25 having a circular opening at the top mar- 70 gined by the folded portion B. A cord or resilient band 26 may be inserted between the walls of this crown portion 25 and may exert a gathering effect upon the folded margin 27 of the circular opening at the top. Thereupon the two walls may be connected at a short distance below the cord 26 by a circular line of stitching 28. The lower portion of the hat may be formed with an inner flat band 14, and outer cylindrical bands 10 and 36, with a brim composed of the lower section A of the blank folded upon itself as above described with reference to Figures 2 to 5 inclusive.

If desired a circular disk of knitted fabric 30 may be secured by the stitches 28 in a position to close the opening in the crown or cover the head of the wearer immediately below the opening. It may be assumed that the hat shown in Fig. 6 is made from the portion of the tube shown in Fig. 1 below the dotted line b—b and that the two upper sections A of that portion of the tube will be disposed one upon the other when folded about the annular center line of the intermediate section B. Therefore when the blank is cut along the line b—b the half section B will tend to roll up in the form of a cylindrical integral cord, and in the folding of the crown forming sections A—A upon each other this cylindrical cord 36 may be brought into substantial contact with the cylindrical band 10, similarly formed at the lower margin of the blank and brought to the base of the crown by the folding of the brim portion as above described. The hat thus produced will therefore have two cord like bands in the angle between the crown and the brim as shown in Fig. 6.

To avoid the opening at the top of the crown as shown in Fig. 6 I may produce a similar hat to that shown in Figures 3 and 4 in which a double walled crown and double cylindrical band is provided, but instead of cutting gores in the top of a crown folded as shown in Fig. 6 in order that the top portion of the crown may be gathered and stitched together, I preferably take a hat like that shown in Figure 4 and form a similar crown independently, after which I stitch it in position with its rolled margin 36 superposed upon the rolled margin 10 and its gored and gathered portions superposed upon the gored and gathered portions 11 and stitched thereto at the peak as clearly shown in Fig. 7.

It will be understood that inasmuch as the brim portion is stretched and fixed in the distended position by ironing and by stiffening material, the folded portion A which forms the brim of the hat may present an area almost equal to that of the entire portion A before folding and stretching. Therefore portions A, of substantially equal dimensions in the tube shown in Figure 1, may be utilized to form either brim or crown portions of the desired dimensions.

I claim:

1. The method of forming knitted hats consisting in knitting a tube continuously, severing the tube into sections, folding an intermediate portion of each section upon itself to form a double walled band, folding one end portion of the section upon itself, and stretching it laterally to form a brim, gathering and shaping the other end portion to form a crown and dampening and pressing the brim portion while stretching it laterally.

2. The method of forming knitted hats consisting in intermediately folding a tube of knitted material upon itself to form an annular double walled band, forming a cylindrical roll at one end of the tube, folding the rolled portion and adjacent portion of the tube upon itself along an annular line substantially midway between the roll and said band to form a brim portion, shaping the other end portion of the tube to form a crown, radially distending and reinforcing the brim portion, with the cylindrical roll adjacent the base of the crown, and stitching the roll and band to the base of the crown.

3. A knitted hat having a crown and a double walled brim formed integrally and having, at the junction of the crown and brim, a double walled knitted band on one side and a knitted cylindrical band on the other side, said double walled band and knitted cylindrical band comprising integral extensions of the respective brim walls.

4. A knitted hat having a crown and a double walled brim formed integrally and having, at the junction of the crown and brim, a double walled knitted band on one side and a knitted cylindrical band on the other side, said double walled band and knitted cylindrical band comprising integral extensions of the respective brim walls, and the crown portion comprising an integral extension of one of the walls of said band.

5. A knitted hat having crown, brim and band formed integrally from a tubular piece of knitted fabric, said brim being double walled, the lower wall thereof constituting an integral extension of the crown and the upper wall thereof having a terminal band at the base of the crown, the outer margin of said upper wall of said brim being in-

tegrally connected with the lower wall of said brim.

6. A knitted hat having a double walled crown and brim provided at their junction with a plurality of knitted cord-like bands at one side of the base of the crown one of said cord-like bands comprising a rolled up margin of one inner wall of the brim and the other constituting a rolled up margin of one wall of the crown and a double walled flat band of knitted material at the other side of the base of the crown.

7. A knitted hat having a crown and brim provided at their junction with a plurality of knitted cord-like bands at one side of the base of the crown and a double walled flat band of knitted material at the other side of the base of the crown, one of said cord-like bands and said flat band being formed integrally with portions of said crown and another of said cord-like bands being formed integrally with a portion of said brim.

8. A knitted hat having integrally formed folded crown and brim portions, and an intermediate portion of one wall folded upon itself and constituting a double walled band at the junction of the crown and brim portions, said brim portion extending radially with its folding line at the outer margin and its inner margin having a rolled up portion secured to the base of said crown.

9. A knitted hat having a crown and a double walled brim formed integrally therewith, the lower wall of said brim comprising an extension of said crown, and the upper wall of said brim having a terminal portion rolled upon itself to form a cord-like band at the junction of said crown and brim.

10. A knitted hat having integrally formed, double walled, folded crown and brim portions, the lower wall of said brim comprising an extension of one wall of said crown, and the upper wall of said brim having a terminal portion rolled upon itself to form a cord-like band at the junction of said crown and brim.
